UNITED STATES PATENT OFFICE.

RICHARD E. HILDEBRAND, OF CHICAGO, ILLINOIS.

SPARK-PLUG INTENSIFIER.

1,353,657.

Specification of Letters Patent. Patented Sept. 21, 1920.

Application filed January 29, 1917. Serial No. 145,043.

To all whom it may concern:

Be it known that I, RICHARD E. HILDEBRAND, a citizen of the United States, residing at Chicago, in the county of Cook and State of Illinois, have invented certain new and useful Improvements in Spark-Plug Intensifiers, of which the following is a specification.

My invention relates to spark plugs for internal combustion engines, and has particular reference to spark intensifiers. The object of the invention is to provide improvements which will make the intensifying spark more certain or dependable by multiplying the points from which the spark may jump; by obviating variations in the spark-gap due to vibrations and burning away of wire electrode points, and by providing a more stable construction generally than heretofore. Another object of the invention is to provide improved means for detecting spark plug troubles and to protect same against the elements, foreign substances, etc.

With the above-named general objects in view my invention consists in the novel construction, combination and arrangement of parts, all as hereinafter described more fully in detail, illustrated in the accompanying drawing and more particularly pointed out in the appended claims.

In the drawing—

Figure 1 is a vertical section through a spark plug with my improvements applied thereto.

Fig. 2 is a section taken substantially on the line 2—2 of Fig. 1.

Fig. 3 is a perspective view of the protective hood for the intensifier attachment, together with the protected parts separated.

Fig. 4 is a modification of Fig. 2.

Fig. 5 is a section taken substantially on the line 5—5 Fig. 2.

Fig. 6 is a section taken on the line 6—6, Fig. 1.

In the several views 2 represents a well known form of spark plug comprising an interiorly threaded lower section 3 with exterior threads 4 to be engaged with a threaded engine bore, and an upper section 5 carrying a porcelain insulator. 6, 7 and 8 are the usual electrodes or firing points and 9 an exteriorly threaded bushing having screw threaded engagement with the section 3 and bearing against a flange 10 on the lower

end of the section 5 that is seated on an annular shoulder 11 on the section 3. The upper end of the electrode wire 7 is a threaded portion 12 on which are nuts 13 and 14 holding therebetween a disk of insulation 15 and a similar disk of metal 16, with the difference that the disk 15 has a small bore 17 for the wire 12 while the disk 16 has a larger opening 18 therein from the edge of which a spark, or a series of sparks, may jump to the central nut 13 and the electrode wire 12, 7. In Fig. 4 this jump-spark edge takes the form of a saw-tooth edge 19 which provides a large number of individual points from which sparks may jump to the central electrode wire. In the peripheries of the disks 15 and 16 are cut notches 20 and 21 which permit the passage of flanges 22 and 23 on the edge of an approximately semi-spherical glass hood 24. By turning the hood after the passage of its flanges through the cut-out portions 20 and 21 the flanges are engaged with the under side of the disk 15. An annular flange 25 above the segmental flanges 22 and 23 engages the upper side of the disk 16. The disks 15 and 16 are provided with projections or extensions 26 through which is a bore 27 that is engaged by a bolt or post 28 on which is a knurled nut 29 and a nut 30 between which is clamped the end of a wire 31 that conducts current to the disk 16. In the horizontal plane of the flanges 22 and 23 the hood 24 has a cut away portion 32 that clears the extension 26.

The above described invention is an improved spark intensifier and spark trouble detector, all combined in a single plug member. The edge of the disk 16 provides a multiple spark gap at which may be noted on the exterior of the engine, by lifting the engine hood, whether or not the plug is operative at the ignition gap within the engine cylinder. The smooth edge 18 or saw edge 19 provides an indefinite number of spark gaps from which a number of sparks may radiate to the central nut, which intensifies the action of the intensifying gap, which is to produce a static current and an induced current which does not seek a short circuit, but is forced to the gap at the sparking ignition end of the plug. At the latter gap the spark is changed from the usual yellow to a much hotter blue flame which tends to keep the plug and cylinder 110

clean, preventing the waste of unexploded gases, obviating the undue wear on the machinery caused by a "missing" engine, and makes the motor start easier. The substitution of the ring gap for the delicate wire ends prevents trouble caused by the latter burning off, prevents the plug from becoming "shorted" through accumulations of soot, carbon, grease, or broken porcelain, 10 prevents the widening of the ordinary gap from jerks and vibrations in the machinery, and the increased spark power obviates trouble from flooding the engine with oil, the plug firing evenly though covered with 15 oil or packed with grease.

The conveniently attachable and removable glass hood protects the plug terminals and insulation from water and oil and thereby helps to prevent short-circuiting.

20 Having thus described my invention, I claim as new and desire to secure by Letters Patent—

1. The combination with a spark plug, of an intensifier on the outer or exposed end 25 of the plug having a ring-form electrode and a central electrode with an annular spark-gap therebetween and a transparent hood inclosing said intensifier.

2. The combination with a spark-plug, of an auxiliary set of electrodes mounted in an 30 exposed position on said spark-plug and producing a jump-spark at the exterior of an engine to which said plug is applied, and a removable hood that protects said electrodes and through which their operation 35 may be observed.

3. The combination with a spark plug and its ignition electrodes to be arranged within an engine, of a centrally disposed electrode on the exteriorly exposed end of said spark- 40 plug, and a circle of electrode points arranged around said centrally disposed electrode.

4. The combination with a spark-plug's exterior and exposed end and the centrally 45 disposed electrode wire having a nut thereon, of an insulated electric current conducting disk having an opening therein which provides a spark-gap around said nut, a transparent hood covering said nut and 50 opening, and means exteriorly of said hood for connecting an electric circuit wire with said disk.

In testimony whereof I have hereunto signed my name.

RICHARD E. HILDEBRAND.
